TONGS

Filed Sept. 18, 1929

UNITED STATES PATENT OFFICE

WILLIAM R. GUIBERSON, OF LOS ANGELES, CALIFORNIA, ASSIGNOR TO THE GUIBERSON CORPORATION, OF DALLAS, TEXAS, A CORPORATION OF DELAWARE

TONGS

Application filed September 13, 1929. Serial No. 392,401.

This invention relates to a casing tongs, and particularly to a tool of the wrench type adapted for use upon the tubing, rods and couplings for oil well work. More specifically the invention refers to the construction of tongs in which the work is surrounded by jaw members connected together and further connected at each end with an operating lever or handle.

10 In tools of such character it is important to provide a strong rigid pivot as the lever is very heavy and exerts much pressure when applied to the jaws. Further the structure of the parts is such that it is difficult to remove and replace the usual pivot when desired, and also to change the position thereof to increase or diminish the dimensional capacity of the jaws.

To obviate objections to previous constructions and provide a novel and improved device, I dispose the pivot between the lever and jaw in an elongated slot at one end of which it is held against rotation while the remainder of the slot is filled by a bushing block fitting 25 the same.

A further object of the invention is to provide a new structure of bearing pin having a rib at one side spaced from and intermediate its end, said rib being adapted to seat in a 30 channel at one end of a slot in one jaw, and a bushing fitting said pin and having a rib seated in a channel at the opposite end of the slot.

Another object of the invention is to provide an improved casing tongs including a lever member, a jaw pivoted thereon, a latch jaw pivoted to the first jaw, a pressure jaw provided with a slot therein, a pin on the handle engaging said opening, and a latch connecting the latch and pressure jaws.

Other and further objects and advantages of the invention will be hereinafter set forth and the novel features thereof defined by the 45 appended claims.

In the drawing:—

Figure 1 is a separated perspective of the jaws and lever;

Figure 2 is an enlarged vertical section 50 through the pivot pin;

Figure 3 is a section on line 3—3 of Fig. 2 with the pivot in one position;

Figure 4 is a similar view with the pivot shifted;

Figure 5 is a detail perspective of the pivot 55 and bushing; and

Figure 6 is a plan of the assembled tool.

Like numerals of reference indicate like parts in the several figures of the drawing.

The tongs may be formed of any desired 60 size or material and the configuration thereof varied at will. The numeral 10 designated the pivoting jaw provided with a lip 11 adapted to enter the bifurcated end 12 of the handle or lever 13 which is suspended in the 65 usual manner as indicated at 14.

A latch jaw 15 is pivoted at 16 to the jaw 10 and carries at its opposite end a latch 17 pivoted thereon at 18 to engage a lip 19 at the outer face of the pressure jaw 20. This 70 latter jaw is formed at its inner end with an arcuate slot 21 adapted to receive a pressure pin 22 carried by the end 12 of the handle and offset from the pivot thereof to effect a leverage.

The pivoting slot 23 in the lip 11 is elongated or oval in shape and formed at each end with an angular key-way 24, each of which ways fitting a radial angular rib 25 carried at one side of the axis of the pivot 80 pin 26, intermediate pintles 27 which fit circular bearings 28 in the end 12 of the lever. To permit the removal of the pivot by tapping it up or down the bearing 28 has recesses 29 to permit the passage therethrough of the 85 rib on the pin, and such recesses will align with the key-ways 24.

The pivot is held at one end of the slot 23 by a bushing or block 30 having a key 31 adapted to seat in one of the ways 24 and firmly retain the pivot at the opposite end of the slot. When it is desired to adjust the area of the jaws for different sizes of pipe or object to be grasped, the pivot is withdrawn and reversed in position at the end of the slot opposite to that previously occupied and the bushing likewise reversed to fill the remainder of the slot. The lip 11 is also formed with an aperture 32 which aligns with an aperture 33 in the handle lever when the 90 95 100

parts are in locking position, and these apertures may receive a locking pin (not shown).

In the operation of the invention the jaws are opened by releasing the latch and are then applied to the object to be gripped. After relatching the jaws the handle lever is swung on its pivot and the pressure pin travelling in the slot of the gripping jaw firmly secures the tongues to the object. For the purpose of providing a readily removable pivot which may be shifted in position yet firmly held against rotation when in use, the pivot pin is interlocked with one end of its slot and held against displacement by the bushing interlocked with the opposite end of the slot. In this shifting of the pivot to vary the capacity of the jaws the pin may be driven out through the slotted bearing in the lever and the bushing then moved laterally and similarly removed. The parts are replaced in like order with the pivot locked at the end of slot opposite to that previously occupied. Means are thus provided for shifting the pivot while the tool is in position for use and without removing the jaws from the lever.

The specific construction of the several parts has been shown and described but the invention is not confined thereto as changes and alterations may be made without departing from the spirit of the invention as recited in the following claims.

What I claim is:

1. In a casing tongs, a handle lever, gripping jaws, a pivotal connection between the lever and one jaw comprising an elongated opening in one member, a pivot pin having means to engage an end of the opening to prevent its rotation, and means for holding said pin held against rotation by engagement with the opposite end of said opening.

2. In a casing tongs, a handle lever, gripping jaws, a pivotal connection between the lever and one jaw comprising an elongated opening in one member, a pivot pin having means to engage an end of the opening to prevent its rotation, and a bushing engaging said pin and interlocked with the opposite end of the opening.

3. In a casing tongs, a handle lever, gripping jaws, one of which is formed with an elongated pivot opening having an angular wall at each end, a pivot pin for said lever provided intermediate its ends with means to seat on said wall, and a holding block engaging the pin and the opposite end wall of the opening.

4. In a casing tongs, a handle lever, gripping jaws, one of which is formed with an elongated slot having a key-way at each end, a pivot pin for said lever having bearing portions at each end and an intermediate rib adapted to seat in one of said ways, and a bushing member engaging said pin opposite said rib and formed with a holding rib to

seat in the way at the opposite end of the slot.

5. In a casing tongs, a handle lever formed with a bifurcated end having bearings therein with recesses at opposite sides, a pivoting jaw having a lip to enter said bifurcation and an elongated slot with key-ways at its opposite ends, a pivot pin having pintles at each end to seat in the lever bearings and an intermediate rib to engage one of said ways, and a bushing block disposed in the lip slot and a curved face to engage said pin and an opposite rib to seat in a key-way of the slot.

6. In a casing tongs, a handle lever formed with a bifurcated end having bearings therein with recesses at opposite sides, a pivoting jaw having a lip to enter said bifurcation and an elongated slot with key-ways at its opposite ends, a pivot pin having pintles at each end to seat in the lever bearings and an intermediate rib to engage one of said ways, and a bushing block disposed in the lip slot and a curved face to engage said pin and an opposite rib to seat in a key-way of the slot, a latch jaw mounted upon the pivoting jaw, a gripping jaw having a slot, a pressure pin upon the lever offset from its pivot and engaging the gripping jaw slot, and a latch connecting the latch and gripping jaws.

7. In a casing tongs, jaw members, a bifurcated lever connected to operate the same, a cylindrical pivot member having pintles at its opposite ends for said lever and an intermediate radial angular rib interchangeably engaging different spaced seats in one of said jaw members, and a bushing engaging said pivot and another of said seats.

8. In a casing tongs, a handle lever, a jaw provided with an elongated slot, a pivot mounted in said slot and formed for interlocking engagement with either end thereof, bearing portions for said handle at either end of said pivot, means for retaining the pivot in engagement with either end of the slot, a latch jaw pivoted to the first jaw, a pressure jaw provided with a slot, a pin on the handle operating in the pressure jaw slot, and a latch connecting the latch and pressure jaws.

In testimony whereof I affix my signature.

WILLIAM R. GUIBERSON.
